UNITED STATES PATENT OFFICE.

LEE E. MOORE, OF BOSTON, MASSACHUSETTS.

BOOT OR SHOE.

SPECIFICATION forming part of Letters Patent No. 317,562, dated May 12, 1885.

Application filed August 2, 1884. (No model.)

To all whom it may concern:

Be it known that I, LEE E. MOORE, of Boston, county of Suffolk, State of Massachusetts, have invented a new and useful Improvement 5 in Boots or Shoes, of which the following is a full, clear, concise, and exact description, reference being had to the drawings accompanying and forming a part hereof, in which—

Figure 1 is a section across the fore part of 10 my shoe after it has been lasted, the right-hand side showing the outsole in position, and the left-hand side showing the insole, upper, and welt as they appear after being secured together. Fig. 2 is a cross-section of the insole 15 used.

The chief object of my invention is to secure a boot or shoe of superior quality and at less cost than that at which goods of the same general kind are now produced. I am able to 20 do this by the method of construction employed, and more particularly by the use of an insole of the peculiar character shown.

My invention will be readily understood 25 from the following description, in which I use letters of reference to the accompanying drawings.

The insole A, shown in cross-section in Fig. 2, and which is necessary for the construction 30 of a boot or shoe in the manner herein set forth, is provided at its upper edge with a feather, a, and at its lower edge with a flange, b, projecting downward, substantially at right angles to the body of the sole. It will be readily seen 35 that in constructing this inner sole the round-edged sole-blank is channeled either directly from the edge, (see right-hand side of Fig. 2.), or on the upper surface some distance in from the edge. (See left-hand side of Fig. 2.) After 40 channelling the sole-blank the portion outside of or below the channel is turned downward substantially at right angles to the body of the sole, and set and pressed in that position.

In constructing my shoe the insole is placed

on the bottom of the last B, the feather a being next the last, and the upper and lining 45 are brought over the last, and over the feather, and placed against the projecting flange b of the insole. A welt-strip is then laid on the outside of the upper, and the whole is then secured together by a line of stitches, as shown 50 at d, Fig. 1.

In the operation of sewing I prefer to use a wax-thread machine fitted with the work-rest and guide attachment patented to James H. Cutten, as shown and described in Letters 55 Patent No. 275,365, dated 10th day of April, 1883.

After the operation of sewing, the projecting flange d, as also the projecting edge of the lining and upper, is trimmed and hammered 60 down, and the filling and outsole are secured in position by a line of stitches (shown at f) passing through the welt and outsole. The boot or shoe is then finished in the well-known manner. 65

I do not wish to be understood as claiming herein the invention shown and claimed in my application No. 139,449, filed simultaneously herewith.

What I claim is—

A boot or shoe having an inner sole provided with a downwardly-projecting flap or flange formed by channeling or slitting the sole inward from or near its edge, in combination with an outer sole, an upper terminating within the outer edge of the outer sole, and a welt, said projecting flap or flange, upper, and welt being secured together by a line of stitches, and said welt and outer sole being secured together by a second line of stitches 75 outside of the first line, substantially as set forth. 80

LEE E. MOORE.
